William M. Hayden
INVENTOR
BY Victor G. Evans

WITNESS: *Verne F. Mueller*

UNITED STATES PATENT OFFICE.

WILLIAM MAXWELL HAYDEN, OF ELROY, WISCONSIN.

DENTIST'S TOOL.

Application filed April 2, 1926. Serial No. 99,393.

My invention relates generally to dentists' tools and more particularly to a certain new and useful improvement in tools especially adapted for retracting tissues in the upper 5 right and left jaw in the malar area for locating posterior dental nerves and the second division of the fifth nerve for access in nerve blocking.

Because of the location of the malar area 10 it is with difficulty that a dentist is able to inject in the posterior dental nerve a solution for anesthetizing this nerve. It is therefore one of the principal objects of the present invention to provide an instrument 15 of the character herein described whereby the tissues in this malar area may be retracted to permit effective and safe injection of the solution for the purpose described.

20 As will be evident from the description to follow, the tool can be utilized generally in the mouth for cleaning and scaling teeth in the malar region as well as for burring cavities in buccal cervical cavities of the 25 malar teeth and for guiding grinding instruments for grinding purposes on the teeth.

In accordance with the various objects of the invention I provide a tool, of the character hereinafter described, wherein 30 there are provided opposed blades curved to conform to the outline of the malar bone whereby by gradually working the tool over the superior maxillary bone the blade is brought into contact with the tissues of the 35 malar zone whereby upon slight operation of the blade the tissues can be sufficiently retracted to permit the injection of a solution for anesthetizing the posterior nerve.

Other objects will appear hereinafter.

40 The invention consists in the combination and arrangement of parts hereinafter described and claimed.

The invention will be best understood by reference to the accompanying drawing, 45 showing the preferred form of construction, and in which

Fig. 1 is an elevational view of the tool embodying the invention illustrating the same in applied position,

50 Fig. 2 is an edge elevational view of the same, and

Fig. 3 is a perspective view of the same.

To accomplish the various objects of the invention I provide a tool generally indicated at A which includes a handle grasping portion 10 defining opposite lateral en-

larged portions 11 defining finger tip engaging portions 12 to facilitate holding the tool in the hand when in use. Extending from these enlarged portions 11 are reduced 60 portions 13. The edges 14 of these reduced portions are curved inwardly and then circle outwardly to provide inwardly extending recesses 15 each of which is adapted when the tool is in applied position, as illustrated in Fig. 1, to receive the adjacent portion of the malar bone 16 when in resting position against the superior maxillary bone 17.

The circled portions 18 define opposed 70 blades 19 substantially circular in outline. These blades 19 are adapted to rest inwardly of the malar bone upon the superior maxillary bone. By gradually working the tool in a reciprocal or swinging manner with 75 lower jaw partially closed in an actual case and swung laterally the tissues in the region of the malar bone can be sufficiently retracted to expose the posterior nerve to permit the injection of a solution for anesthet- 80 izing this nerve.

As illustrated in Fig. 1 of the drawing the blades 19 extend in opposite direction with respect to each other. The object of extending these blades in opposite direction 85 is to permit operation of the tool on either the left or right side of the jaw. The edges 14 of the reduced portions 13 are likewise curved in opposite direction for the purposes above mentioned.

90 In grinding the tool can be positioned in a location within the mouth so as to dispose the blade 19 in a position to guard the tissues in the malar region from injury by engagement with the grinding instrument.

95 In using the tool for cleaning and scaling purposes it is obvious that the blades, by reason of the curvature, can be brought into contact with the teeth for the purpose.

As illustrated in Fig. 2 the reduced end 100 portions 13 and the blades 19 are curved in opposite direction in an upwardly and downwardly direction from the longitudinal axis of the tool. The reason for this is to permit expeditious insertion of either blade 105 in the mouth to be disposed in the region of the malar bone for retracting the tissues for the purposes herein mentioned.

110 While I have illustrated and described the preferred form of construction for carrying my invention into effect, this is capable of variation and modification without de-

parting from the spirit of the invention. I, therefore, do not wish to be limited to the precise construction set forth, but desire to avail myself of such variations and modifications as come within the scope of the appended claims.

Having described my invention, what I claim as new and desire to secure by Letters Patent is:

1. A dental tool including a body defining a hand grasping portion, there being a recess formed inwardly in the body to receive the malar bone when the tool is in operation, and a blade defined by the body outwardly of the recess, said blade being adapted for resting position against adjacent portions of the superior maxillary bone.

2. An instrument for retracting tissues from the malar bone region including a body defining an enlarged portion providing a finger tip engaging portion and a reduced portion defining a recess adapted to receive adjacent portions of the malar bone when the tool is in applied position, and a blade defined by the body outwardly of the recess, said blade being adapted to be brought into contact with tissues adjacent the superior maxillary bone.

3. An instrument for retracting tissues

from the malar bone region including a body defining an enlarged portion providing a finger tip engaging portion and a reduced portion defining a recess adapted to receive adjacent portions of the malar bone when the tool is in applied position, and a blade defined by the body outwardly of the recess, said blade being adapted to be brought into contact with tissues adjacent portions of the superior maxillary bone, said blade and said reduced portion being curved from the longitudinal axis of the body.

4. A dental tool comprising a handle portion and an end portion substantially circular in outline and disposed angularly to said handle portion, the formation of said end portion being such that when the tool is inserted into the mouth, said end portion will retract the tissues highly above the apices of the molar roots behind the zygomatic or malar process of the superior maxillary bone for locating points of injection for anesthetizing the posterior nerve or the second division of the fifth nerve.

In testimony whereof I affix my signature.

WILLIAM MAXWELL HAYDEN.
